Primary Examiner — Philip S Hyder*Assistant Examiner* — Ramzi S Almatrahi(74) *Attorney, Agent, or Firm* — Finnegan, Henderson, Farabow, Garrett & Dunner, L.L.P.(57) **CLAIM**

The ornamental design for a panoramic camera, as shown and described.

DESCRIPTION

FIG. 1 is a top, front and right side perspective view of a panoramic camera showing our new design; FIG. 2 is a top, rear and left side perspective view thereof; FIG. 3 is a bottom, front and left side perspective view thereof;

FIG. 4 is a top, front and left side perspective view thereof; FIG. 5 is a front elevation view thereof; FIG. 6 is a rear elevation view thereof; FIG. 7 is a left side elevation view thereof; FIG. 8 is a right side elevation view thereof; FIG. 9 is a top plan view thereof; and, FIG. 10 is a bottom plan view thereof.

The broken lines shown in the drawings illustrate portions of the panoramic camera that form no part of the claimed design.
